UNITED STATES PATENT OFFICE.

FREDERICK L. KEPPLER, OF NEW YORK, N. Y.

DESIGN FOR AN ASH-TRAY.

• 50,390.

Specification for Design.

Patented Feb. 27, 1917.

Application filed February 10, 1916. Serial No. 77,534. Term of patent 14 years.

To all whom it may concern:

Be it known that I, FREDERICK L. KEPPLER, a citizen of the United States, residing at New York, in the county of New York and State of New York, have invented a new, original, and ornamental Design for Ash-Trays, of which the following is a specification, reference being had to the accompanying drawing, forming part thereof.

Figure 1 is a plan,

Fig. 2 is a bottom plan; and
Fig. 3 is a side elevation of an ash tray showing my new design.

I claim:

An ornamental design for an ash tray as shown.

FREDERICK L. KEPPLER.
